(57) **CLAIM**

The ornamental design for an embossed envelope label, as shown and described.

DESCRIPTION

FIG. 1 is a front view of an embossed envelope label, according to one preferred embodiment of this invention; FIG. 2 is a top view of the embossed envelope label, as shown in FIG. 1; FIG. 3 is a side view of the embossed envelope label, as shown in FIG. 1; and, FIG. 4 is a cross-sectional view of the embossed envelope label, as shown in FIG. 1.

The structure depicted by means of broken lines in FIGS. 1 through 3 has been shown for illustrative purposes only and forms no part of the claimed design.
